VERNE L. CAMERON, OF ESCONDIDO, CALIFORNIA

FENDER STRAIGHTENING TOOL

Application filed April 29, 1932. Serial No. 608,309.

This invention relates to a contrivance or tool which is especially constructed for reconditioning distorted sheet metal, the same being particularly desirable for use in reshaping automobile fenders by removing dents and restoring the metal to its original form and shape.

I am aware of the fact that it is not broadly new to provide a tool for accomplishing this task. So far as I am aware, I do not know of any accessory, appurtenance, appliance or tool having the characteristics of the improved device constituting the subject matter of this invention.

The foregoing assertion is predicated upon the belief that the improved tool herein illustrated and described is desirable in that it includes an appropriately shaped frame having companion convex disks located in close proximity to each other and adjustably supported on the frame for idling rotation in order to secure the requisite degree of freedom, adjustment and motion for acting on the sheet metal between the disks in a manner to reform damaged portions and smooth the metal in such a manner to restore it to its original condition.

My primary aim is to generally improve upon tools of this character by providing one which undoubtedly fulfills the requirements of an invention of this type due to the special selection of parts and the mechanical coordination which provides for uniformity and dependability in action and such other factors as are necessary in sustaining my claim.

In the drawings:

Figure 1 is an elevational view of a tool constructed strictly in accordance with the preferred embodiment of the invention showing the operation and relationship of the parts.

Fig. 2 is an enlarged detail sectional and elevational view illustrating the association and arrangement of the structural details more explicitly.

Fig. 3 is a sectional view taken approximately on the plane of the line 3-3 of Fig. 1.

Figs. 4 and 5 are detail perspective views

of the adaptor fixture constituting mountings or carriers for the work engaging members.

Referring now to the drawings by distinguishing reference characters, it will be observed that the numeral 6 designates a C-shaped clamp having upper and lower arms 7 and 8 adapted to straddle the fender or other work acted on. The upper arm 7 is somewhat shorter than the lower arm 8 and the latter arm has its extended end portion formed into a centrally apertured disk-like base 9. The companionate work engaging devices have certain common characteristics and are distinguished by the reference characters 10 and 11 respectively. The lower device 11 as seen in Fig. 5 comprises a longitudinally elongated tubular body or shell 12 whose lower end portion 13 is formed to provide a foot and the foot is provided with an eccentric screw threaded stud 14 extending through the aperture in the base 9 to accommodate a retaining nut 15. As seen in Fig. 2, the tubular body 12 is enlarged at its open end to form a cup 16 to accommodate an end thrust anti-friction bearing unit 17. The tool proper comprises a stem 18 having a convex work engaging head 19 and formed at its inner end with a groove 20. The stem extends into and through a bushing or sleeve 21 mounted in the body. The diameter of the head 19 is considerably larger than the cup so that the marginal portions over hang the peripheral wall of the cup.

The fixture 10 comprises a similar tubular body 22 having a cup 23 containing the end thrust bearing 24 to accommodate the shoulder portion on the tool stem 25 just beneath the opposed convex work engaging head 26. The stem is also grooved as at 27 and the grooved portion of the stem fits into the bushing or sleeve 28. The numerals 29 in both instances, designate set screws extending through the body, the bushing and into the grooves to provide the desired detachable swivel connection of the tool in the shell or body. The numeral 30 designates a channel shaped rocker arm which is formed integral with body 22 and extends at the angle 100

shown and terminates in a feed nut 31 for the threaded portion 32 of the crank or set screw 33. The set screw is engageable with the adjacent portion of the arm 7. The arm 7 extends between the flanges of the channel-shaped arm 30 and is pivotally connected thereto as indicated at 34. Thus the fixture 11 is a relatively stationary one, while the fixture 10 is adjustable toward and from it.

10 It is to be observed that the longitudinal axis of the tool stem 25 is at a substantially obtuse angle with respect to the corresponding axis of the tool stem 18 whereby to dispose the tool in the approximate angular relationship seen in Fig. 2. Hence, when the convex heads 19 and 26 are together, or approximately so, their contacting surfaces are eccentric of the axis of the tool stem. This is essential in order to provide the requisite 15 freedom of action of the free rotatable or swivelly mounted tool.

Particular attention is called to the eccentric connections of the stud 14 to the adjacent end portion 9 of the frame. This allows the fixture 11 to be bodily adjusted on this eccentric axis to vary the relationship of the companion disk or heads 19 and 26. In other words, this confines the adjustment to a degree which makes it possible to manipulate the tool accurately and properly.

The principle idea is to provide a frame of a shape to engage over the fender with a pair of convex disk-like work engaging elements, these being freely rotatable in bearings, the bearings being in somewhat opposed relation and carried by similar attaching devices. The attaching devices are detachably and adjustably mounted on the free end portions of the arms of the frame so that 25 they may take the position seen in Fig. 1 or somewhat similar positions according to the shape of the work being reconditioned. The lower bearing and its roller or disk becomes a substantially fixed member while the upper one is adjustable toward and from it and held in a set position by the feed screw or crank which may be fed or backed up as the case may be.

With this arrangement the free circular portion permitted from the turnable disks is sufficient to restore the proper shape and contour of the sheet metal. This tool is usually successful for "rubbing out" the excess metal caused by dents and bulges, either 30 shrinking it or distributing it into a larger area and leaves the contour true enough as to seldom require filing or filling.

The axes on which the shafts are mounted are generally inclined with respect to each other causing the pressure to be applied to the disk between the center and the periphery on one side of the center. The device is clamped on the damaged surface in the manner of an ordinary C clamp and 35 is operated by grasping at proper points

and propelling it back and forth over the surface.

I claim for this invention, the application of an entirely new and a different principle from that employed in prior art tools designed to accomplish a similar purpose. A new principle is embodied in the free rotating action of two convex surfaces, so mounted that they may be set at varying angles and positions to each other, and thus adaptable to any portion of the metal or automobile fender, whether near the automobile body or the outer bead of the fender or otherwise. The method of engaging or pinching of the metal between the offset discs gives a powerful fulcrum-like force, not otherwise obtained. The rotating motion on a free shaft tends to a natural return of the distorted metal to its original position.

It is thought that the description taken in connection with the drawings will enable a clear understanding of the invention to be had. Therefore a more lengthy description is thought unnecessary.

While the foregoing description of the invention has been shown and described, it is to be understood that minor changes coming within the field of the invention claimed may be resorted to if desired.

Having thus described my invention, what I claim as new is:—

1. A tool of the class described comprising a substantially C-shaped frame, a pair of companion fixtures pivotally, adjustably and detachably mounted on the terminal ends of the arms of said frame, each fixture including a tubular bearing having a cup, an end thrust bearing in each cup, a convex work engaging disk, a shaft connected thereto and extending through the bearing, retaining means for the shaft, the disks being engageable with the end thrust bearings in said cups, and an adjusting screw carried by one of the fixtures and cooperative with the adjacent end of said frame for holding it in a predetermined adjusted position.

2. A device of the class described comprising a substantially C-shaped clamp having a relatively short upper arm and a proportionately longer lower arm, the extending free end portion of the lower arm being formed into a disk-like terminal centrally apertured, a tool mounting having a foot engageable with said disk-like portion, a threaded stud carried by the foot and extending through the aperture in said disk-like portion to accommodate a retaining nut, said stud being disposed eccentrically with respect to the longitudinal axis of the mounting, a tool comprising a stem swivelly mounted in said mounting and having a convex work engaging head.

3. A device of the class described com-

prising a substantially C-shaped clamp having a relatively short upper arm and a proportionately longer lower arm, the extending free end portion of the lower arm being
5 formed with a disk-like terminal centrally apertured, a tool mounting having a foot engageable with said disk-like portion, a threaded stud carried by the foot and extending through the aperture in said disk-
10 like portion to accommodate a retaining nut, said stud being disposed eccentrically with respect to the longitudinal axis of the mounting, a tool comprising a stem swivelly mounted in said mounting and having a convex work engaging head, together with a similar companion tool unit comprising a fixture including an arm pivotally attached intermediate its ends to the free end of the upper clamp arm, an adjusting set screw
20 carried by the inner end of said fixture arm and engageable with the adjacent clamp arm, a tubular body attached to the opposite end of the fixture arm, and a swivelly mounted tool in said body including a stem and a convex head opposed to said first-named head, the stems of the respective tools being disposed in general obtuse angular relationship with respect to each other, whereby to provide the desired offset action of the tools
25 30 which allows the heads to come together in eccentric contacting relationship.

4. In a structure of the class described, a C-shaped clamp, one arm of said clamp being extended beyond corresponding ends of the remaining arm of the clamp, a relatively stationary tool and mounting eccentrically attached to the extended end portion of the first-named arm, a bracket pivotally attached intermediate its ends to the second named clamp arm, adjusting and retaining means for said bracket, and a tool on the free swingable end of the bracket arm opposed to said first-named tool, both of said tools including cooperating convex disk-like heads.

In testimony whereof I affix my signature.

VERNE L. CAMERON.
